P. HICKEY,
CAN FOR PUTTING UP ALKALI.

No. 75,547.

Patented Mar. 17, 1868.

United States Patent Office.

PATRICK HICKEY, OF PHILADELPHIA, PENNSYLVANIA, ASSIGNOR TO HIMSELF AND ROBERT PORTER, OF THE SAME PLACE.

Letters Patent No. 75,547, dated March 17, 1868.

IMPROVEMENT IN CANS FOR PUTTING UP ALKALIES.

The Schedule referred to in these Letters Patent and making part of the same.

TO ALL WHOM IT MAY CONCERN:

Be it known that I, PATRICK HICKEY, of the city of Philadelphia, and State of Pennsylvania, have invented certain new and useful Improvements in Putting in the Heads of Cans designed for holding Alkalies, Paints, and such like substances; and I do hereby declare the following to be a full, clear, and exact description of the same, reference being had to the accompanying drawings making a part of this specification, in which—

Figure 1 represents a section through one of the cans with the bottom set in, and the top in its condition when ready to have the head laid into its place preparatory to its being permanently secured there, as will be explained.

Figure 2 represents a similar section through one of the cans after the head is set and fastened in, and showing the collar or tool against which the metal is pressed in fastening in the head.

Figure 3 represents a top plan of the can with the collar or tool in place.

It has been found to be exceedingly difficult to make a tin or other sheet-metal can that would hold alkalies, paints, and such other substances, and in particular tight enough to prevent the leakage from destroying the labels on the cans, or staining them, which injures their marketable or salable value, and wastes the contents. In putting such material into cans the head must be left out, so that the material can be readily put in. When the can is filled, it must be kept in an upright position, and held very firmly or steadily whilst the head is being fastened in, to prevent the contents from being shaken out or spilled. To solder in the heads is expensive and troublesome, and must be done at the works where packed.

My invention has for its object not only the facilitating of the operation of putting in the heads of cans that are filled with alkali or other such-like penetrative material, but to cheapen the operation, and make a better joint than has heretofore been done, and by which plan I can dispense with the use of solder.

To enable others skilled in the art to make and use my invention, I will proceed to describe the same with reference to the drawings.

The can I prefer to make cylindrical, though other forms may be used if found desirable, or for close packing in square boxes. The bottom, A, of the can is set into the body B in the same manner that the head is, but before there is anything in the can, and when it can be turned or held in any manner, and is comparatively a simple operation. The top of the body B is swaged out into the form shown in fig. 1, that is, with a bevelled shoulder, 2, and a concentric flange, 3, which shoulder and flange enlarge the cylinder or body sufficiently to allow the head C to be laid into its place. This head C, like the bottom, A, may be stamped out, with sunken and raised portions or corrugations, to give it stiffness, and has upon it a flaring flange, 4, that will lie against and on the inside of the bevelled shoulder 2 of the body B, as seen in fig. 1.

When the can is filled with the material it is to hold and contain, the head C is laid into its place, and then a steel or other metal collar, D, is put around the body B and against the bevelled shoulder 2, the edge of said collar being chamfered off to snugly fit against said bevelled shoulder, and whilst the can is in its upright position and the collar clasped around it, the flange 3 is turned and set down against the flange 4 of the head C, which makes a perfectly tight joint, sufficiently so without soldering to hold the most volatile or penetrative substances. The collar D, to facilitate its placing and removal, is hinged at a, fig. 3, and diametrically opposite the hinge there is a tongue-and-mortise, lap, or clasp-joint, b, for holding the ends of the collar together when in position for serving as an anvil to set the joint against. When the head C is being put in, the can may remain stationary upon the bench, table, or stand.

By thus turning the body of the can over upon the heads, the joint or line of union is such that if there should be even the least escape of vapor or gas from the inside it would not reach the label which is on the body, and hence not destroy or stain it. And whilst no pressure that could occur inside of the can could force out the heads, yet when access to the contents of the can is desired, by striking upon the inside of the flange, and driving it outward, the head may be readily removed.

Having thus fully described my invention, what I claim therein as new, and desire to secure by Letters Patent, is—

Setting the heads into alkali, paint, or other similar cans, by means of the flanges 2, 3, 4, and a collar, D encircling the body, so that said heads may be permanently and tightly set into the body whilst full, and sitting in an upright position, substantially as described, and for the purpose set forth.

PATRICK HICKEY.
